INDIRECT-LIGHTING FIXTURE

Application filed April 22, 1929. Serial No. 357,001.

My invention relates to the class of indirect lighting fixtures in which the lamp bulb is laterally housed by a reflector which redirects the light upwardly, and in which this reflector is housed by an opaque bowl.

In some of its general objects, my invention aims to provide a simple, strong and inexpensive lighting unit of this class which will permit convenient access to the interior of the reflector for cleaning the latter, which will firmly support the reflector from its bottom and without requiring auxiliary fastening elements for supporting the reflector, which will not cause a cracking of the reflector by temperature changes in the reflector and bowl, and which will permit both a ready inserting of the reflector in the bowl and a removal of the reflector from the bowl.

Furthermore, my invention aims to provide a bowl construction for such a reflector which can easily be manufactured and which will not impose undue strains on the reflector housed by the bowl.

Illustrative of my invention and of more detailed objects of my invention—

Fig. 1 is a front elevation of my indirect lighting unit as it appears when in use, with one half of the bowl and reflector in section.

Fig. 2 is a plan view of the same unit, drawn on a reduced scale.

Fig. 3 is an elevation of the same unit, drawn on the same scale as Fig. 2, showing the bowl and reflector swung out of its normal position for access to the interior of the reflector.

Fig. 4 is an enlarged horizontal section through the arms which support the bowl, taken along the line 4—4 of Fig. 1 and looking upward.

Fig. 5 is an enlarged and fragmentary side elevation of a portion of the same unit, looking from the line 5—5 of Fig. 1.

Fig. 6 is an enlarged and fragmentary perspective view showing one of the hinging connections between the bowl and the arms which support the bowl.

Fig. 7 is a central and vertical section through the bottom of my indirect lighting fixture, showing the disposition of the reflector with respect to the bottom of the bowl

when no cushioning disk is interposed between them.

Fig. 8 is a fragmentary vertical section through the socket housing and adjacent parts, taken along the line 8—8 of Fig. 4. 55

In the illustrated embodiment, the incandescent lamp 15 is supported by a socket disposed within an upright socket housing 1, which socket is not pictured, since it forms no part of my present invention. To support a reflector bowl from this socket housing 1, I provide three flat arms 2, each of which arms has its upper portion 2A extending upwardly into the said socket housing and bearing flatwise against the bore of the housing. 60 Each of these upper arm portions is clamped against the housing by a knurled screw 3 and is kept from rotating about this screw by the entry of an embossed nub 4 in a corresponding perforation in the housing. Thus 70 arranged, a single screw serves for rigidly securing each of the said arms 2 to the socket housing, and when the screws are tightened, all of the arms are held against swinging or misalignment. 75

These arms are preferably spaced uniformly about the vertical axis of the socket housing, and the part of each such arm which is below the socket housing is twisted adjacent to the housing at right angles to the upper 80 arm portion and bent edgewise so that the lower end portion of each arm extends substantially horizontally. The tip 2B of each such lower arm portion overhangs the inwardly directed horizontal mouth flange 5 85 of an upwardly opaque bowl which bowl is desirably formed of sheet steel.

One such arm tip 2B (as shown in Fig. 5) extends between the parallel riser webs 7 of two angle-shaped punchings 8, each of which has its base portion fastened to the bowl flange 5, as by a rivet 9; and this arm tip 2B is normally secured to both of the said punchings by a detachable member, such as a spring cotter 10 extending through alined perforations in the said arm tip and the riser webs 7 of the punchings. 90

Each of the other two arms has its lower and outwardly directed end bent to dispose this end in a parallel to the arm tip 2B, and 100

each such bent arm end 2C is pivoted on a rivet 20 extending through the riser 11 of a pivoting punching which has its base 12 secured to the top of the bowl flange by a rivet 13, this assembly being shown separately in Fig. 6. These pivoting punchings are disposed (as shown in Fig. 2) so that the pivoting rivets 20 have a common axis, and so that the risers 11 are both parallel to the risers of the punching 8 through which latter riser 10 detachable spring cotter 10 extends.

Housed by the bowl is an upwardly open reflector 14, this reflector desirably being of glass silvered on its outer face and ribbed or otherwise configurated to avoid the projecting of images of the filament of the incandescent lamp 15 which depends from the socket housing. The reflector 14 has its mouth end sufficiently large in diameter so as to underhang the bowl flange 5, and has a height approximating the interior height of the bowl. The bottoms of the bowl and the reflector are desirably convexed downwardly, and the lower end of the reflector may seat directly on the bottom of the bowl, as shown in Fig. 7, in which case the convexing of the reflector bottom is preferably greater than that of the bowl bottom 6, thereby limiting the interengaging of these parts to a small area. However, I may interpose a cushioning disk 16 between the bottom of the reflector and the bottom of the bowl, as shown in Fig. 1. In either case, the reflector can be of such a height that it reaches close to the bowl flange 5, provided that the diameter of the mouth end of the reflector is only slightly smaller than the bore of the bowl just below the flange 5, so that this bore portion of the bowl will center the reflector.

To allow for the use of a reflector having a mouth of greater diameter than the bore of the flange 5, I make the bowl of two parts, including a lower main portion 6 having a cylindrical collar 6A at its upper end, which cylindrical portion is of larger diameter than the mouth of the reflector, and a bowl ring fitted upon this main bowl portion. This bowl ring comprises an upright and tubular lower end portion 5B telescoped into the said collar 6A, and an inwardly and upwardly curving intermediate part 5A, and the aforesaid inwardly directed top flange 5.

By forming the intermediate bowl ring part 5A so that the bore of its upper portion is only slightly larger than the diameter of the mouth end of the reflector, I enable this bowl ring portion to center the reflector in the bowl. When the reflector has been inserted in the main bowl portion, the bowl ring is slipped over the mouth end of the reflector so as to telescope the ring portion 5B into the bowl collar 6A, and the two bowl parts are then secured to each other by screws 17.

With the reflector-housing bowl of my unit

thus composed of two parts having telescopically interfitting peripheral portions, the two interfitting portions together afford a quite stiff peripheral part, so that my bowl will readily retain its shape even if made of relatively thin metal. Hence I can employ metal which can easily be drawn to an artistic curvature, and by making the interfitting portions 5B and 6A considerably larger in diameter than the mouth end of the bowl, I avoid the need of following the shape of the reflector, which shape necessarily is determined largely by the desired distribution of the reflected light. Furthermore, I can readily ornament the tubular collar portion 6A, if desired.

Moreover, by vertically elongating the perforations in the bowl collar 6A, through which perforations the screws 17 extend, I permit the bowl ring to be slid snugly down upon the mouth end of the reflector according to the exact height of the latter, thereby clamping the reflector against the bottom of the bowl when the screws 17 are tightened. The reflector is then held rigidly, so that it will not shift in position even if its mouth is somewhat smaller than the upper part of the collar portion 5A. So also, the relatively large diameter of the interfitting tubular portions permits the main bore part 6 (with the possible exception of a small central bottom portion) to be freely spaced from the glass reflector, so that accidental impact against the bowl from any side of the latter will not damage the reflector.

By disposing the hinging arm ends 2C so that they are both parallel to the detachable third arm end 2B, I also permit the entire bowl and reflector assembly to be swung down at a considerable angle, while still remaining securely supported through the non-detachable hinging rivets 20, as shown in Fig. 3. This makes the cleaning of the reflector both easy and safe. So also, by twisting the supporting arms 2 as above described, I not only secure rigidity for these arms but also dispose the flat faces of their main portions upright, so as to reduce the shadows cast by these arms.

Moreover, by supporting the reflector from the bowl bottom on which it seats, I entirely avoid the use of screws underhanging mouth portions of the reflector, thereby eliminating the cracking and breaking of the mouth flanges of reflectors which occurs so frequently when reflectors are supported by screws in the heretofore customary manner.

However, while I have heretofore described my invention in an embodiment including numerous desirable details of construction and arrangement, I do not wish to be limited to these, as changes may obviously be made without departing either from the spirit of my invention or from the appended claims. Nor do I wish to be limited to the

employment of all novel features of my invention.

I claim as my invention:

1. An indirect lighting fixture comprising an upwardly open reflector having a downwardly convexed lower end, and a bowl housing the same; the bowl having an upwardly concaved bottom portion supporting the reflector and an annular upper end portion clamped down upon the mouth end of the reflector.

2. An indirect lighting fixture comprising an upwardly open reflector having a downwardly convexed lower end, and a bowl housing the same; the bowl comprising a main bowl part having a central bottom portion supporting the reflector and having a tubular upper end, and a bowl ring having a lower portion telescopically fitting and secured to the said tubular end of the main bowl part, the bowl ring having at its upper end an inturned flange overhanging the mouth end of the reflector.

3. An indirect lighting fixture comprising a socket housing, a lamp depending from the housing, a plurality of rigid arms fast on the housing and extending downwardly and outwardly from the housing, a reflector underhanging the housing and into which the lamp extends, and an opaque bowl housing the reflector and supporting the reflector from the bottom of the latter, two of the said arms having parallel outer ends non-detachably hinged to the bowl, and means detachably connecting the outer end of the third arm to the bowl.

4. In an indirect lighting unit, an opaque bowl and upwardly open bowl having an inturned annular flange at its mouth end, a reflector housed by the bowl and having a central bottom portion seated on the bottom of the bowl, the reflector having its mouth end underhanging the said flange, the interior diameter of the said mouth end being substantially equal to that of the bore of the said flange, the outside diameter of the said reflector mouth end approximating the bore of the portion of the bowl below and adjacent to the said flange, whereby the said bore portion centers the reflector in the bowl.

5. In an indirect lighting fixture, an upwardly open and upwardly flaring reflector, and an urn-shaped bowl housing the reflector and slightly taller than the reflector; the bowl comprising a main bowl portion shorter than the reflector, and a bowl ring fitted upon and secured to the upper end of the main bowl portion; the bowl ring having at its upper end an inturned flange overhanging and adjacent to the mouth end of the reflector, the portion of the bowl ring adjacent to the said reflector mouth end having a bore approximating the outside diameter of the said mouth end so as to center the reflector in the bowl; the reflector having its

bottom seated on the bottom of the bowl and the bowl having all parts between its said bottom and the said bore portion freely spaced from the reflector.

6. In an indirect lighting fixture, an upright and upwardly flaring reflector, and a substantially urn-shaped bowl housing the same; the upper end part of the bowl comprising an annular flange overhanging and close to the mouth end of the reflector and of a bore approximating that of the said reflector mouth end; the reflector having its lower end seated on a relatively small bottom portion of the bowl and having its mouth end centered in the reflector by the bore portion of the bowl adjacent to the said flange, the bowl being formed so that all portions thereof between its said small bottom portion and its said reflector centering portion are freely spaced radially of the bowl from the reflector.

7. In an indirect lighting fixture, an upwardly open reflector having a downwardly convexed lower end; and a substantially urn-shaped bowl housing the reflector and consisting of upper and lower parts secured to each other at the largest diametered portion of the bowl; the lower bowl part having its lower end engaging a relatively small lower end portion of the reflector; the upper bowl part having a portion surrounding and adjacent to the mouth end of the reflector so as to center the said mouth end in the bowl, the upper bowl part also having portions closely overhanging the mouth end of the reflector to prevent a tipping of the reflector in the bowl, the last named portions being spaced from the axis of the reflector by distances at least equal to the radius of the mouth end of the reflector.

8. In an indirect lighting fixture comprising an upwardly flaring reflector and a substantially urn-shaped opaque bowl housing and supporting the reflector; the reflector being seated on the bottom of the bowl; the bowl having an annular mouth end portion closely adjacent to the mouth end of the reflector so as to center the reflector in the bowl, the bowl having at its mouth end an inwardly directed flange sufficiently close to the mouth end of the reflector to prevent a tipping of the reflector in the bowl, the said flange having a bore at least equal to that of the mouth end of the reflector.

Signed at Chicago, Illinois, April 19th, 1929.
